(57) **CLAIM**

The ornamental design for a handle cover, as shown and described.

DESCRIPTION

FIG. 1 is a front and left side perspective view of a handle cover, showing our new design;

FIG. 2 is a front view thereof;

FIG. 3 is a left side view thereof;

FIG. 4 is a rear view thereof;

FIG. 5 is a right side view thereof;

FIG. 6 is a top view thereof;

FIG. 7 is a bottom view thereof;

FIG. 8 is a cross-sectional view along lines 8-8 of FIG. 7;

FIG. 9 is a front and left side perspective view of a handle cover, showing another embodiment of our new design;

FIG. 10 is a front view thereof;

FIG. 11 is a left side view thereof;

FIG. 12 is a rear view thereof;

FIG. 13 is a right side view thereof;

FIG. 14 is a top view thereof;
